[57] CLAIM

The ornamental design for an interfacing cassette for use with a defibrillator or the like, as shown and described.

DESCRIPTION

FIG. 1 is a front perspective view of an interfacing cassette for use with a defibrillator or the like showing our new design;

FIG. 2 is a front elevational view thereof;

FIG. 3 is a right side elevational view thereof;

FIG. 4 is a left side elevational view thereof;

FIG. 5 is a back elevational view thereof;

FIG. 6 is a top plan view thereof; and

FIG. 7 is a bottom plan view thereof.

Fig. 1.

Fig. 2.

Fig. 3.

Fig. 4.

Fig. 5.

Fig. 6.

Fig. 7.
